Primary Examiner — Keli L Hill(74) *Attorney, Agent, or Firm* — JEEN IP LAW, LLC(57) **CLAIM**

The ornamental design for a speaker cover, as shown and described.

DESCRIPTION

FIG. 1 is a front, right and bottom perspective view of a speaker cover, showing our new design;
 FIG. 2 is a rear, left and top perspective view thereof;
 FIG. 3 is a front view thereof;
 FIG. 4 is a rear view thereof;
 FIG. 5 is an enlarged top plan view thereof;
 FIG. 6 is an enlarged bottom plan view thereof;
 FIG. 7 is a left view thereof;
 FIG. 8 is a right view thereof;
 FIG. 9 is an enlarged view of area “9” in FIG. 1;
 FIG. 10 is an enlarged view of area “10” in FIG. 1; and,
 FIG. 11 is an enlarged view of top area in FIG. 2.
 The broken lines shown in the drawings illustrate portions of the speaker cover that form no part of the claimed design. The dot-dash broken lines depict the boundaries of the enlargements that form no part of the claimed design.
